UNITED STATES PATENT OFFICE.

GEORGE J. MUNSCHAUER, OF BUFFALO, NEW YORK.

IMPROVEMENT IN BIRD-CAGES.

Specification forming part of Letters Patent No. 136,611, dated March 11, 1873.

To all whom it may concern:

Be it known that I, GEORGE JOHN MUNSCHAUER, of Buffalo, in the county of Erie and State of New York, have invented certain new and useful Improvements in Self-Locking Devices for Bird-Cages, &c., of which the following is a specification:

This invention relates to devices for securing the detachable bottoms to bird-cages, &c.; and consists in providing the common hinged bent-wire catch with a sliding self-locking device which prevents the catch from becoming accidentally unclasped or detached, as herein-after described.

In the drawing, Figure 1 is a sectional elevation of a cage, showing the locking device. Fig. 2 is a plan of the lock.

A represents the cage; B, the detachable bottom; and C, the usual base-piece, over which the bent-wire clasps or hooks D D hold. The clasps are made in the usual manner and hinged to the detachable bottom, and have arranged on their upper part a tin or other metal lock or catch, E, bent in the form shown, and having their two ends c c' bent loosely around the wires of the loop, so that they will slide up and down thereon and cause the other point, d, to slide down between the holding-loops e e' of the hook, and thus lock the base-piece C firmly between the clasp D and point d, as shown. By this means the clasp is held se-

curely in place, and prevents the possibility of the bottom becoming detached or loosened unless the locks b b are raised up, as at F, Fig. 1, when the hook may be bent back out of the way in the usual manner. When put back the catch drops of itself, thus forming a self-locking device; or they may be secured to the loop a sufficiently tight to prevent its being too readily detached, so that if the cage should be by accident overturned the locks will remain intact.

This simple device overcomes the great trouble of detachable bottoms which, with the present locks, are apt to become loose and fall to the ground, or leave an opening for the escape of the bird.

I claim—

The plate E formed with the end c c' for attachment to the clasp D, and with the point d for working between the wires e e' of the clasp, as set forth, the several parts operating in respect to each other and to the cage A and the bottom B, as herein shown and described.

In witness whereof I have hereunto signed my name in the presence of two subscribing witnesses.

GEO. J. MUNSCHAUER.
